UNITED STATES PATENT OFFICE

ROSA MAY PICKARD, OF WILMETTE, ILLINOIS

DESIGN FOR A WALL PLATE FOR LIGHTING FIXTURES

Application filed March 9, 1931. Serial No. 39,009. Term of patent 7 years.

To all whom it may concern:

Be it known that I, ROSA MAY PICKARD, a citizen of the United States, residing at Wilmette, in the county of Cook and State of Illinois, have invented a new, original, and ornamental Design for a Wall Plate for Lighting Fixtures, of which the following is a specification, reference being had to the accompanying drawings, forming part thereof.

Fig. 1 is a front view showing my new design; and

Fig. 2 is a side view.

I claim:

The ornamental design for a wall plate for lighting fixtures as shown.

ROSA MAY PICKARD.
